UNITED STATES PATENT OFFICE.

ORMOND E. HUNT, OF DETROIT, MICHIGAN, ASSIGNOR TO PACKARD MOTOR CAR COMPANY, OF DETROIT, MICHIGAN, A CORPORATION OF MICHIGAN.

FLUID-COMPRESSOR FOR MOTOR-VEHICLES.

1,394,835.

Specification of Letters Patent. Patented Oct. 25, 1921.

Application filed September 30, 1918. Serial No. 256,265.

To all whom it may concern:

Be it known that I, ORMOND E. HUNT, a citizen of the United States, and resident of Detroit, Wayne county, State of Michigan, have invented certain new and useful Improvements in Fluid-Compressors for Motor-Vehicles, of which the following is a specification.

The present invention relates to compressors and more particularly to the type adapted for use in motor vehicles to produce a pressure in the fuel tank for the purpose of forcing the fuel to the carburetor of the motor.

15 The principal object of the invention is to provide a machine of the character mentioned with means for varying the pressure to which the gas may be compressed.

To this end the invention consists in the provision of means for adjusting or varying the volume of the clearance space of the compressor.

Other objects and features of novelty will be apparent from the description taken in connection with the drawings in which:

Figure 1 is an elevation mostly in section illustrating one embodiment of the present invention;

Fig. 2 is a transverse sectional elevation 30 of the pump shown in Fig. 1, the crank case being an elevation;

Fig. 3 is a sectional view taken substantially on the line 3—3 of Fig. 1;

Fig. 4 is a sectional view taken substantially on the line 4—4 of Fig. 1.

Referring to the drawings the numeral 10 indicates the crank case of a compressor constructed in accordance with the present invention. As shown it is formed with an opening 11 in one side which registers with an opening 12 in the front end of the crank case 13 of a hydrocarbon motor. The crank case 10 may be secured to the crank case 13 in any suitable manner as by means of the bolts 14. A hollow cylinder 15 is mounted on the crank case 10 and secured thereto by the studs 16. A cup shaped piston 16, open at the top and closed at the bottom, is slidably fitted in the cylinder 15. Any suitable mechanism may be employed for reciprocating the piston. As shown, a shaft 17 driven in timed relation with the hydrocarbon motor has an eccentric 18 secured thereto within the crank case 10. An eccentric rod 19 is operatively associated with the eccentric

and has its free end pivotally connected to the piston 16 as by means of the wrist pin 20.

Midway of its ends the piston is formed with an annular peripheral groove 21 which has communication with the interior of the piston through apertures 22 in the wall thereof. The cylinder wall is formed with an inlet port 23 which is positioned to register with the groove 21 when the piston is at the lower end of its stroke. As clearly illustrated in Fig. 4 the cylinder is formed with a boss 24 which has a recess 25 formed therein, the open side of which is closed by a screen 26 secured to the boss by the cap 27. The port 23 leads from the recess 25 to the interior of the cylinder.

From the foregoing it will be seen when the piston is at the lower end of its stroke, air is admitted to the compressor through the port 23 and apertures 22. When the piston reaches the upper end of its stroke the groove 21 registers or comes into communication with a discharge port 28 formed in the wall of the cylinder and the boss 29. The outer end of the port 28 is closed by a plug 30, and a duct 31 arranged substantially at right angles to the port 28 has a check valve 32 disposed therein to prevent return flow of the compressed air discharged from the cylinder. The upper end of the duct 31 is closed by a plug 33. The boss 29 is also formed with a passage 34 leading from the duct 31 to an L 35 which is threaded as at 36 for the connection of a pipe for conveying the compressed air to a point where it is desired to be used.

The principal feature of the invention consists in the provision of means whereby the pressure to which the air is compressed may be substantially any predetermined amount. As shown in the present embodiment of the invention, this object is accomplished by the provision of means for varying the volume of the clearance space of the compressor. As clearly shown in the drawings the upper end of the cylinder 15 is enlarged as at 37 and the upper open end thereof is closed by a cylinder head 38. As illustrated this head has a sleeve 39 extending toward the piston which is exteriorly threaded and screwed into the enlarged cylinder end 37. The interior of the sleeve 39 is also threaded and a partition or plug 40 is screwed therein. The interior of the

22
sleeve thus forms a chamber in communication with the interior of the cylinder and this chamber together with the space above the piston when it is at the upper end of 5 its stroke form the clearance space of the compressor. It is apparent that the volume of this clearance space may be varied by adjusting the partition or plug 40 within the sleeve 39. For the purpose of holding 10 the plug in adjusted position a bolt 42 is threaded through the same at its upper end adapted to bear against the cylinder head.

15 In the operation of the compressor, the piston is reciprocated as previously described. When at one end of its stroke air is supplied thereto through the inlet port 23. As the piston travels toward the other end of its stroke the air within the cylinder is compressed and discharged when it 20 reaches the upper end of its travel through the discharge port 28. If it is desired to increase the pressure to which the air is compressed, then the clearance space of the compressor is decreased by adjusting the plug 25 or partition 40 toward the piston. In the drawings the plug 40 is illustrated at one end of its adjustable movement, that is the position which provides the largest clearance space.

30 Although an embodiment of the invention has been described in detail it is to be understood that the invention is not so limited but includes modifications and changes which come within the scope of the appended 35 claims.

Having thus described the invention what is claimed as new and desired to be secured by Letters Patent is:—

40 1. In a machine of the character described, in combination, a hollow cylinder, a piston fitted to reciprocate therein, a head closing one end of the cylinder having a sleeve projecting toward the piston and a

partition within said sleeve mounted for axial adjustment. 45

2. In a machine of the character described, in combination, a hollow cylinder, a piston fitted to reciprocate therein, a head closing one end of the cylinder having a sleeve projecting toward the piston, and a 50 partition having threaded engagement with the interior of said sleeve.

3. In a machine of the character described, in combination, a hollow cylinder, a piston fitted to reciprocate therein, a head closing one end of the cylinder having a sleeve projecting toward the piston, a plug 55 adjustably fitted in said sleeve, and means to lock the plug in adjusted position.

4. In a machine of the character described, in combination, a hollow cylinder, a piston fitted to reciprocate therein, a head closing one end of the cylinder having a sleeve on the cylinder side thereof, a plug threaded in said sleeve, and a locking bolt 60 threaded through said plug and having one end engaging said head whereby the plug is secured in adjusted position.

5. In a machine of the character described, in combination, a hollow cylinder, a piston fitted to reciprocate therein, a head closing one end of the cylinder having a sleeve projecting toward the piston, said sleeve being exteriorly threaded and screwed into the cylinder, and a partition within 70 said sleeve mounted for axial adjustment. 75

6. In a machine of the character described, in combination, a hollow cylinder, a piston fitted to reciprocate therein, a head closing one end of the cylinder having a sleeve projecting toward the piston, said sleeve being exteriorly threaded and screwed into the cylinder, and a partition threaded 80 within said sleeve for axial adjustment.

In testimony whereof I affix my signature. 85
ORMOND E. HUNT.
